UNITED STATES PATENT OFFICE.

JOHN FRIIS, OF CHICAGO, ILLINOIS, ASSIGNOR TO THOS. CUSACK COMPANY, OF CHICAGO, ILLINOIS, A CORPORATION OF NEW JERSEY.

ELECTRIC SWITCH.

1,227,605.

Specification of Letters Patent.

Patented May 29, 1917.

Application filed November 2, 1914. Serial No. 869,741.

To all whom it may concern:

Be it known that I, JOHN FRIIS, a citizen of the United States, and a resident of Chicago, in the county of Cook and State of Illinois, have invented certain new and useful Improvements in Electric Switches; and I do hereby declare that the following is a full, clear, and exact description thereof, reference being had to the accompanying drawings, and to the letters of reference marked thereon, which form a part of this specification.

This invention relates to improvements in electric switches and consists of the matters hereinafter described and more particularly pointed out in the appended claims.

The invention relates particularly to electric switches for use with electric signs where the electric circuit, including the lamps which illuminate the sign, is intended to be periodically broken and closed. In apparatus and switches included for such service, mechanism with a timed movement is used.

In apparatus of the kind described, the movable member of the switch device generally approaches the contact, with which it is to engage, with the slow movement of the timed apparatus which controls the periods of making and breaking of the switch connection to determine the lighting and extinguishing of the electric lamps. The result of the slow movement of the movable member of the switch device controlling the electric lamp circuit, particularly when breaking the connection between said movable member and the fixed member of the switch, is that arcing is produced between the two switch members, with the consequent deleterious effect to the contact members of the switch and of waste of electric power.

The object of the present invention is to produce a time controlled switch mechanism of the kind referred to, in which the movable member of the switch is quickly and rapidly moved from its contact with the fixed member of the switch, in breaking the circuit, no matter how slow may be the movement of the parts in the timed movement required to determine the period between the making and breaking of the electric circuit. The advantages of my improvement will appear more clearly as I proceed with my specification.

In the drawings:

Figure 1 is a view representing a side elevation of a switch of the kind described, embodying my invention.

Fig. 2 is a view representing a side elevation of the switch looked at from the opposite side from that shown in Fig. 1.

Figs. 3 and 4 are views representing side elevations similar to Fig. 1, except that the parts are shown as they appear in successive periods of the operation of the switch.

Fig. 5 is a top plan view of the switch.

Fig. 6 is a view representing a vertical section through Fig. 5 in a plane indicated by the line 6—6 thereof.

Fig. 7 is a view indicating a partial section through Fig. 1 in a plane indicated by the line 7—7 thereof.

Figs. 8, 9 and 10 are detail elevations of parts to be referred to later in the specification.

Referring now to that embodiment of my invention illustrated in the drawings,—10 indicates a base upon which the parts of the switch mechanism are mounted. 11 indicates an upright bracket plate rising from the base 10, and 12 indicates a horizontal plate supported at the top of said bracket plate 11. On the upright bracket plate 11, there is supported in suitable bearings 13 a horizontal drive shaft 14. 15 indicates a pulley fixed on said shaft and adapted to be to be driven from any convenient motor (not shown). On the shaft 14 is keyed a worm 16 which engages a worm wheel 17 journaled on a horizontal stud 17^a attached in any convenient way to the upright plate 11.

In the case of the switch mechanism shown herein, the worm 16 and the worm wheel 17 comprise the timing mechanism of the switch and determine the periods at which the circuit or circuits controlled by the switch are to be made or broken.

On the top of the plate 12 is mounted an insulation block 18. At each end of said insulation block are attached binding posts 19, 19, which are electrically connected with upright, laterally spaced, fixed, duplex switch blades 20 constructed to contact with the usual knife blades on the movable member of the switch mechanism. Each pair of switch blades 20 constitute terminals in an electric circuit supplying the lamps on a sign or like device (not shown), and usually a sign which bears electrically illuminated

characters on different parts, as for example, on opposite sides, which are intended to be alternately illuminated, the one being dark when the other is illuminated.

- 5 21 indicates the movable member of the electric switch. In the case illustrated, said movable member carries knife contacts for each of the fixed blade contacts above referred to. The movable member 21 comprises a flanged plate 22 journaled in upright bearing arms 23, 23 fixed to the horizontal plate 12; insulation blocks 24, 24 fixed to said plate; and U-shaped bars 25, 25 affixed to the ends of said blocks and each bent to form knife contacts 25^a, 25^a adapted to co-act with and provide electrical connection between the switch blades 20, 20 at the respective ends of the plate 18.

20 The movable switch carrying plate 22 is constructed so as to carry the pairs of knife contacts 25^a, 25^a in planes at an angle to each other, so that when one set of knife contacts 25^a is engaged with its associated blade contacts 20, the other set of knife contacts 25^a will be disengaged from their associated blade contacts 20.

30 On the rock shaft 22^a adjacent one end of the plate 22 (and as shown in the drawings, in the plane of the upright plate 11 on the inside of the bearing arm 23 for the movable switch blade 22) is rotatively mounted an upright rocking plate 26. On the outside of the said bearing arm and in vertical alinement below the axis of oscillation 35 of said rocking plate 26 is rotatively mounted a bell crank lever 27. The lever 27 has arms 27^a, 27^a, which each carry laterally extending pins 27^b, 27^b. At the bottom of the oscillating plate 26 and at either 40 side of its center of oscillation are formed cams 26^a, 26^a which are adapted to be engaged by the pins 27^b on the bell crank lever 27 in a manner presently to be described in the operation of the apparatus. The plate 45 26 has laterally extending pins 26^c, 26^c, which are adapted to coact in alternation with the top of the plate 22 to swing the same on its rock shaft 22^a.

28 indicates an arm pivoted to swing on 50 the shaft 22^a on which is mounted the rocking plate 26 and the rocking switch plate 22. A contractile, coiled spring 29 connects a pin 28^a located below the rock shaft 22^a on the arm 28 with a pin 26^b fixed to a 55 radial, upright extension or arm 26^d made rigid with the rocking plate 26 and located symmetrically with reference to the cam surfaces 26^a, 26^a on said plate. The arm 28 is connected by a pitman 30 to a crank 60 pin 17^b on the worm gear 17 which acts to drive the switch mechanism. On the arm 28 is a laterally extending pin 28^b which engages in a radial slot 27^c formed in the arm 27 one-half way between the 65 pins 27^b carried by said arm. Said pin,

by its coaction with said slot, acts to swing the bell crank lever 27 in one direction or the other as the arm 28 is swung.

The operation of the switch mechanism is as follows:—As will be apparent from the drawings, the continuous rotation of the worm gear 17 by the worm 16 will produce a slow oscillation of the arm 28, first in one direction and then in the opposite direction. Starting with the apparatus in the position shown in Fig. 1, the knife contacts 25^a at the left hand side of the switch mechanism are engaged with their associated blade contacts 20, so that the circuit controlled by that part of the switch mechanism is closed, and the knife contacts 25^a, at the right hand side of the switch mechanism, are disconnected from their associated blade contacts, so that the electric circuit controlled by said part of the switch mechanism is broken. With the parts in this position, the plate 26 is held in a position to the left of the rock shaft 22^a by means of its connection through the coiled spring 29 with the rock arm 28, and the bell crank lever 27 has been rocked to the left by means of the engagement of the pin 28^b carried thereby in the slot 27^c of said bell crank lever. In this position of the parts also, the left hand pin 27^b carried by the bell crank lever 27 is engaged under the left hand cam surface 26^a of the rocking plate 26, while the left hand pin 26^c of the plate 26 is engaged against the top of the plate 22.

As the gear 17 continues to rotate clockwise, as indicated by the arrow, the rock arm 28 is swung to the left into the position indicated by the dotted lines in Fig. 1. This movement of the parts will apparently cause the bell crank lever 27 to swing downward toward the left by reason of the engagement of the pin 28^b in the slot 27^c of the bell crank lever so as to depress the pin 27^b below its co-acting cam surface 26^a on the cam plate 26. Thus, the movement of the gear 17 and of its crank pin 17^b from the position shown in full lines to the position shown in dotted lines, and in addition from the position shown in dotted lines through an angular movement equal to that in going from the position shown in full lines to the position in dotted lines, will have no effect upon the rocking plate 26. As the gear continues to rotate beyond the last named position, however, the arm 28 is swung to the right and with it is swung the bell crank lever 27. This movement of the bell crank lever swings the pin 27^b carried thereby at the left upwardly so that said pin, coacting with the associated cam surface 26^a on the cam plate 26, acts to swing the cam plate to the right slowly. With the movement of the large gear, the knife contacts 25^a on the left gradually rise and the knife contacts 25^a on the

right gradually descend until finally a position as shown in Fig. 3, is reached. In this movement of the parts, the coiled spring 29, the radial arm of the plate 26 and the rock arm 28, gradually approach a position of vertical alinement. As soon as the position of vertical alinement of the parts is reached and passed through, the coiled spring acts to instantly shift the plate 26 to the right. As a result of this movement, the right hand pin 26^b carried by said plate is caused to forcibly engage the plate 22 and swing it to the right, so as to instantly disconnect the knife contacts on one side (the left side, as above described) and connect the knife contacts and its associated switch blades on the other side (the right side.) The cam surfaces 26^a are so formed with relation to the bell crank lever 27 and its pins 27^b that when this movement occurs, the pin 27^b on the side toward which the switch is moving (in the case described, the right side) will not be struck by the associated cam surface until the knife contact 25^a (at the right) reaches its seat in its associated blade contact. In Fig. 3, the parts are shown in the position they occupy just as the shifting movement above described is broken, and Fig. 4 represents said parts after said shifting movement has been accomplished.

I now have the parts in the same position which they occupied as first described, except that they are reversed, and the operation is as before, the engagement of the pin 28^b carried by the rock arm 28 in the slot 27^c of the lever 27 again shifting the bell crank lever with its pin away from the plate 26 during the movement of the gear required to carry its crank pin which is connected to the rock arm 28 down below the horizontal diameter in the gear.

In order to reduce the shock when the movable switch member is shifted as described, elastic strips 30^x are fixed to the top of the fixed insulation block 18 in position to be engaged by associated members 30^a carried by the movable switch member 21, in this case the bolts, by means of which the insulation blocks 24 are attached to the rocking plate 22.

I claim as my invention:

1. An automatic switch device comprising fixed contact members, a fulcrum, a rocking switch member having contacts adapted to make and break connection with said fixed contacts, said rocking switch member being mounted on said fulcrum, a swinging arm mounted coaxially with said switch member, a rocker pivoted vertically below said fulcrum and directly actuated by said swinging arm, a second rocker fulcrumed coaxially with said rocking switch member, said second rocker being provided with lost motion devices for engagement

with said rocking switch member and the first mentioned rocker also being provided with lost motion devices for engagement with the second rocker, and elastic means connecting said second rocker at a point above its rocking axis with said swinging arm at a point below its axis. 70

2. An automatic switch device comprising a base, fixed contact members on said base, a fulcrum, a rocking switch member mounted on said fulcrum, a swinging arm also mounted on said fulcrum, a rocker fulcrumed on said base in a plane spaced from the said fulcrum, a second rocker mounted on said fulcrum, means operatively connecting said swinging arm with the first mentioned rocker, devices on said rocker adapted to actuate said second rocker but with lost motion between them, means on said second rocker adapted for operative engagement with said rocking switch member after said second rocker has moved through a predetermined distance, a spring connecting said second rocker at a point spaced outwardly from said fulcrum with said swinging arm 90 intermediate its ends and means for imparting movement to said swinging arm. 80

3. An automatic switch comprising a base, contact members fixed on said base, a shaft, a rocking switch member having contacts adapted for engagement with said fixed contacts, fulcrumed on said shaft, a swinging arm mounted on said shaft, a rocker having a slot fulcrumed on said base in a plane below said shaft, a stud on said swinging arm operatively engaged in the slot in said rocker, a second rocker fulcrumed coaxially with said shaft, said first rocker having studs adapted to actuate said second rocker after said first rocker has traveled through a part of its movement, means on said second rocker adapted for operative engagement with said rocking switch member after said rocker has moved through a predetermined distance, and a spring connecting said second rocker at a point above its fulcrum to said swinging arm at a point intermediate its ends. 100 105

4. An automatic switch comprising a base, contact members fixed on said base, a shaft, a rocking switch member having contacts adapted for engagement with said fixed contacts, fulcrumed on said shaft, a swinging arm mounted on said shaft, a rocker having a slot fulcrumed on said base in a plane below said shaft, a stud on said swinging arm operatively engaged in the slot in said rocker arm, a second rocker fulcrumed coaxially with said shaft, said first rocker having studs adapted to actuate said second rocker after said first rocker has traveled through a part of its movement, means on said second rocker adapted for operative engagement with said rocking switch member after said rocker has moved through a pre- 110 115 120 125 130

determined distance, a spring connecting said second rocker at a point above its fulcrum to said swinging arm at a point intermediate its ends, and cushioning means on said base adapted to be engaged by said rocking switch member.

5. An automatic switch device comprising a base having fixed contacts and a movable contact member mounted on said base and 10 adapted to periodically make and break connection with said fixed contact, a rocker adapted for operating said movable switch member and having parts for engagement with said movable switch member to bring it 15 into electrical connection with the said fixed contacts on said base, an auxiliary rocker pivotally mounted on said base below the fulcrum of said rocking switch member, said rocker having fixed parts adapted for en-

gagement with said operating member for movement of the same when said movable switch member is being removed from engagement with said fixed contacts, a reciprocating swinging arm fulcrumed coaxially with said rocking switch, a pin carried by 25 said swinging arm and operatively connected to said auxiliary rocker, and a spring fixed to said rocker above its fulcrum and to said swinging arm below its fulcrum.

In testimony, that I claim the foregoing 30 as my invention I affix my signature in the presence of two witnesses, this 3rd day of October, A. D. 1914.

JOHN FRIIS.
